UNITED STATES PATENT OFFICE.

GIRARD DUDLEY KELSEY, OF PATERSON, NEW JERSEY.

POCKET ELECTRIC LIGHTER.

Application filed January 26, 1926. Serial No. 83,907.

This invention relates to an improved pocket electric lighter and has for an object to provide a construction wherein a protected filament is provided, the same being associated with a battery and other parts whereby the filament may be discharged when in use.

Another object of the invention is to provide an electric lighter capable of use in the pocket wherein the parts are of a size for snugly fitting into the pocket of an ordinary garment with means acting as a combined cover for the lighting member and switch for controlling the current to the lighting member.

A still further object, more specifically, is to provide a pocket lighter wherein a removable lighting element is provided and means for connecting the same electrically with a source of current for heating the lighting element when in use.

In the accompanying drawing—

Figure 1 is a longitudinal vertical sectional view through a lighter disclosing an embodiment of the invention.

Figure 2 is a top plan view of the structure shown in Figure 1.

Referring to the accompanying drawing by numerals, 1 indicates a casing of metal or other desired material in which a dry cell 2 is positioned. A bottom 3 is provided for casing 1, said bottom being hinged to the casing at 4 with the free or swinging end normally held in a closed position by a spring catch 5 snapping over a slight projection 6 extending from the lower part of casing 1. The bottom 3 is swung to an open position whenever it is desired to remove or apply a battery. As indicated particularly in Figure 1, battery 2 is provided with a resilient terminal 7 and a stationary terminal 8. At the end opposite bottom 3, a cone-shaped section 9 is either formed integral with the top or end member 10 or is rigidly secured thereto. The member 9 is provided with a section of threads 11 coacting with the threaded section 12 of a removable cone 13. The cone 13 is preferably made from metal and carries a bottom plate 14 secured thereto by solder or otherwise, said bottom plate supporting a tube 15 of porcelain or other insulating matter, a filling 16 of insulating material and a metallic reflector 17. This reflector is not primarily intended to reflect light but to act as a pocket for restricting the heat to

substantially a given point. The reflector 17 is soldered or otherwise secured to the cone 13 and is provided with a projection 18 over which the spring hook or extension 19 is adapted to snap when the cover 20 is closed. This cover is pivotally mounted at 21 on the casing 1 and has rigidly secured thereto a resilient arm 22, said arm having preferably a loop 23 so as to increase the resiliency. The arm 22 is adapted to press tightly against the stationary contact 8 when the cover 20 is open so that this arm and the cover form a combined cover and switch for opening and closing the circuit of the lighting or heating element 24. This heating element may be a resistance wire of any desired kind connected preferably at 25 to a conductor 26, which conductor extends through an insulating member 27, said insulating member being positioned within the tube 15 and held by friction therein. At the lower end the conductor 26 is provided with an enlarged knob or head 28 which is also of conducting material, said head continually engaging the resilient contact 7. One end of the heating element 24 is connected at 29 by solder or in any other desired manner to the reflector 17 so that whenever arm 22 is engaging contact 8, the circuit will be closed and current will flow through the heating element 24 which is of such a resistance as to permit the battery 2 to cause the member 24 to become almost incandescent when the battery 2 is properly connected.

When the heating element 24 is red hot or almost incandescent, a cigar, cigarette or the like may be readily lighted therefrom and after this has been done, lid 20 may be closed which will protect the heating element as well as protect the clothes of the person carrying the device. In addition, the closing and locking closed of the lid 20 will move the arm 22 for breaking the circuit of the heating element and will hold said arm out of engagement with the contact 2. It will be noted, therefore, that there is no separate switch to be operated when the device is to be used but merely the opening of the lid 20 fully will automatically turn the current on and as soon as the device has been used the current is automatically turned off by closing the lid.

What I claim is:

1. A pocket electric lighter comprising a dry cell having a pair of terminals, a cas-

- ing for said dry cell formed with a conical-shaped portion at one end, a cone-shaped socket fitted into said conical-shaped portion, a heating element carried by said 5 socket member, means extending from said heating element to a point exteriorly of the socket member and to a position in engagement with one of said terminals, and a combined lid and switch for said socket member, said combined lid and switch having a resilient arm adapted to engage one of said contacts when the same is fully open whereby the circuit of said heating element is closed.
- 15 2. A pocket electric lighter comprising a heating element, a cone-shaped structure carrying said heating element and enclosing the same on all sides except one, a casing formed with a cone-shaped depression, said 20 cone-shaped structure being removably mounted in said cone-shaped depression, a dry cell arranged in said casing, said dry cell being formed with a pair of contacts, one of said contacts being in permanent 25 electrical connection with said heating element, and switch means for connecting the other terminal of the source of current to said heating element and a cover for said cone-shaped structure, said cover being 30 formed with an arm of said switch, said arm being movable to close said switch when the cover is moved to an open position and moved to open said switch when the cover is moved to a closed position.
- 35 3. A pocket electric lighter comprising a casing having a depressed portion at one end, a removable cone structure mounted in said depression, a dry cell arranged in said casing, means for connecting one terminal 40 of said dry cell to said cone structure, a heating element carried by said cone structure having one end engaging the cone structure and the opposite end insulated therefrom, said opposite end being positioned to engage the second terminal on said

dry cell, and manually actuated means for opening and closing the circuit of said heating element, said manually actuated means normally acting as a cover for said heating element.

4. A pocket electric lighter comprising a casing having a cone-shaped depression in one end, said depression being open at the bottom, a cone-shaped structure removably mounted in said cone-shaped depression, a metallic cone-shaped reflector arranged in said cone-shaped structure, a heating element arranged in said reflector and contacting therewith at one point, means extending from said heating element to a point exteriorly of said cone-shaped structure, a source of current arranged in said casing positioned with one contact in engagement with said means, a resilient switch arm pivotally mounted on said casing and adapted when in one position to engage the second contact of said source of current, said switch arm being electrically connected with said reflector, and a manually actuated member for actuating said switch, 65 said manually actuated member being formed of sheet material and acting as a lid to cover said reflector.

5. A pocket electric lighter comprising a dry cell having a pair of terminals, a casing for said dry cell formed with an opening, a socket member fitted into said opening, a heating element carried by said socket member, means extending from said heating element to a point exteriorly of the 75 socket member and to a position in engagement with one of said terminals and a combined lid and switch for said socket member, said combined lid and switch having a resilient arm adapted to engage one 80 of said contacts when the lid is fully opened, whereby the circuit of said element is closed.

GIRARD DUDLEY KELSEY.
